FREDRICK F. MACLEAN, OF SYRACUSE, NEW YORK.

LIGHT-DEFLECTOR FOR HEADLIGHTS.

1,119,709.

Specification of Letters Patent.

Patented Dec. 1, 1914.

Application filed October 1, 1912. Serial No. 723,341.

To all whom it may concern:

Be it known that I, FREDRICK F. MACLEAN, a citizen of the United States, and resident of Syracuse, in the county of Onondaga, in the State of New York, have invented new and useful Improvements in Light-Deflectors for Headlights, of which the following, taken in connection with the accompanying drawings, is a full, clear, and 10 exact description.

This invention relates to certain improvements in light-deflectors for head lights of the class commonly used on motor vehicles, such as street cars, automobiles, motor boats and the like, but is equally applicable to search lights and similar devices where it is desired to concentrate and project the rays of light considerable distances through space from a suitable lamp or burner through the 20 medium of a reflector. It is well known that these lights, which are greatly intensified by reflection, tend to momentarily, at least, obscure the vision of approaching pedestrians or drivers of vehicles and this is particularly true of automobiles and similar fast moving vehicles approaching each other, frequently causing accidents or damage to one or both of the machines.

Various devices, such as dimmers and 30 shutters, have been proposed for subduing or cutting off the reflected light and, while they are effective in preventing their reflected rays from being projected directly into the eyes of approaching pedestrians, horses and drivers of vehicles, it is equally true that this dimming or obscuring of the light brings about practically the same dangers to traffic that would exist in driving the cars without lights.

40 The main object, therefore, of my present invention is to provide a lamp or head light with simple means, operable at will, for deflecting rather than diminishing or obscuring the reflected rays of light downwardly directly in front of the moving vehicle upon which the lamp is mounted so as to always maintain a strong reflected light directly ahead of the car but sufficiently low down to avoid the projection of such 50 rays into the eyes of approaching pedestrians, horses or drivers of other vehicles.

Another object is to construct the deflector in such manner that it may be folded or telescoped into compact space when not

in use or easily and quickly adjusted to any 55 degree within an arc of approximately 90 degrees when necessary.

A further object is to provide means for automatically retracting or returning the telescoping sections of the deflector to their 60 normal inoperative position.

Other objects and uses will be brought out in the following description.

In the drawings—Figure 1 is a front elevation of a head light showing my improved 65 deflector in operative position therein. Fig. 2 is a side elevation of the greater portion of the same head light with the deflector in the same position. Fig. 3 is a front elevation of the same head light showing the 70 deflector as folded to its inoperative position. Fig. 4 is a longitudinal sectional view partially in elevation of the head light showing the deflector in its folded positions but in section. Fig. 5 is an enlarged detail 75 sectional view through a portion of one side of the deflector and adjacent portion of the case showing more particularly one of the pivotal studs or screws for said deflector and the retracting spring for returning the 80 sections of the deflector to their normal positions. Fig. 6 is an enlarged detail sectional view through a portion of the folded deflector and adjacent part of the casing upon which it is mounted. Fig. 7 is a side 85 elevation of a portion of the head light shown in Fig. 3, the deflector being folded. Fig. 8 is an enlarged side elevation of one side of a deflector showing a modified means of imparting motion from one section to the 90 other. Fig. 9 is a sectional view through one side of two of the adjacent sections of the deflector shown in Fig. 7.

In order that my invention may be clearly understood, I have shown an electric 95 lamp —1— as suitably secured in the apex of a suitable reflector —2— which together with the lamp is mounted within an inclosing case —3— having a transparent plate —4— across the open side of the reflector, 100 it being understood that any other suitable lamp or burner may be substituted for the electric lamp —1—. The casing —3— is in this instance circular and tubular for receiving in its open end the reflector —2— 105 and casing —3— constitutes what may be termed a head light or search light and is similar to that commonly used on motor

vehicles, such as street cars, automobiles, motor boats and the like.

The front end of the casing —3— is provided with an annular enlargement or head —3'— upon which is pivotally mounted my improved deflector —5— which is composed of a series of, in this instance five, semi-circular arched segments or sections —6— having a maximum width at the center substantially equal to the corresponding width of the head —3'— from front to rear as shown more clearly in Fig. 6.

This deflector is arranged wholly at the exterior of the case and pivoted so as to swing forwardly and downwardly across the upper portion only of the open side of the reflector —2— or transparent plate —4— so as to deflect the reflected rays of light from the lamp downwardly and forwardly and for this purpose the opposite ends of the deflector sections —6— are mounted upon pivotal studs or screws —6'— which are secured in diametrically opposite sides of the case —3— as shown more clearly in Fig. 5.

The central upper portion of the rear edge of the casing —3— is provided with an upwardly projecting limiting stop shoulder —7— having a yielding buffer —8— of rubber or other suitable material on its front face adapted to be engaged by the rear edges of the sections —6— when folded to their normal inoperative positions shown in Figs. 3, 4, 6 and 7.

The central upper portions of the front of the casing —3— and telescoping sections —6— of the deflector are provided with hook-shaped limiting stops —9— for interlocking engagement with similar but reversed hook-shaped shoulders —10— on the central upper portions of the rear edges of the next superposed sections —6— thereby limiting the forward and downward rocking movement of each of said sections relatively to each other and to the upper portion of the casing —3— to approximately the width from front to rear of such upper portion of the casing or head —3'—.

The front edge of the outermost deflector section —6— is provided with a pendant flange —11— extending inwardly or radially a distance corresponding to the radial depth of the combined sections —6— and adjacent side of the casing —3— when the deflector sections are in their normal or inoperative positions as shown in Fig. 6, said flange constituting means for returning the remaining deflector sections to their normal positions in which all of the sections are yielding held by a retracting spring —12— shown in Fig. 5. Suitable means is provided for operating the deflector from its normal position against the action of the retracting spring —12— and for this purpose one side or end of the outer-

most section —6— is provided with a crank arm —13— normally extending below the adjacent stud or screw —6'—.

An operating member —14—, consisting in this instance of a cord or cable, is connected at one end to the crank arm —13— and has its opposite end extending to any suitable part of the vehicle within convenient reaching distance of the operator and is adapted to be manipulated by hand or foot.

The pivoted ends of the deflector sections —6— lie in close proximity one against the other although free to turn easily upon their respective pivots while the intermediate portions which telescope with each other are spaced slight distances apart to permit the free operation and interlocking engagement of the shoulders —10— with the shoulders —9— and also affording air passages to reduce the resistance and thereby preventing accidental closing of the sections by impact with the air particularly when the vehicle is in rapid motion, it being understood that the shoulders —9— and —10— are comparatively short circumferentially or lengthwise of the sections —6—.

In Figs. 8 and 9, I have shown a modified means for imparting rocking motion from one to the next adjacent deflector section, such means consisting in providing the pivotal ends of one section with lateral projecting lugs —10'—, moving in relatively short slots —16— in the adjacent sections, the length of said slots or recesses being just sufficient to allow each segment to move through an arc substantially equal to its circumferential width before operating the next adjacent section.

Operation: In operation, the deflector sections —6— are normally held in their folded position as shown more clearly in Fig. 6 by means of the retracting spring —12— and flange —11— which is also provided upon its inner face with a buffer similar to the buffer —8—, the tension of the spring being sufficient to prevent rattling or relative movement of the sections —6— one upon the other or upon the casing —3—. By pulling upon the cord or cable —14—, the sections —6— may be rocked successively from their normal positions against the action of the spring —12— to any intermediate position within an arc of substantially 90 degrees to which the movement of the sections are limited by the stop shoulders —9— and —10—. In this manner the reflected rays of light from the lamp through the medium of the reflector —2— may be deflected downwardly below the horizontal plane of the lamps and, therefore, below the horizontal plane of the eyes of a pedestrian, horse or driver of an approaching machine and, at the same time, throwing a light of full intensity a considerable distance ahead of the machine upon

which the deflector is mounted but below such horizontal plane. Another feature of advantage of this deflector is that, when it is adjusted for use, the reflected rays of light 5 are also thrown back under the machine, which, in many instances is advantageous particularly when it is necessary to make an inspection or repairs around or under the machine. As soon as the pulling upon the 10 cord or cable —14— is released, the spring —12—, aided by the flange —11—, automatically returns all of the deflector sections to their normal positions or in a plane within the front and rear edges of the head 15 —3'— of the head light case.

What I claim is:

1. In combination with a lamp case having a transparent front plate, a light-deflector hingedly mounted upon the exterior 20 of the case and movable to and from a position across the upper portion only of the transparent plate and a stop on the top of the case for limiting the upward and rearward movement of the deflector.
- 25 2. In combination with a lamp case having a transparent front plate, a light-deflector composed of telescoping arched sections movable about a common axis to and from a position across the upper front portion only of said case, a spring for returning the outer section, and means on the outer section for returning the remaining sections.
- 30 3. In combination with a lamp having a reflector, a light-deflector composed of telescoping arched sections movable about a common axis to and from a position across the upper front portion only of said case, a spring for returning the outer section, and means on the outer section for returning the remaining sections.
- 35

scoping arched sections movable about a common axis to and from a position across a portion of the open side of the reflector, the outermost section having a flange projecting across one edge of the remaining 40 sections to move the latter in one direction when said outer section is moved in the same direction.

4. In combination with a lamp, a casing for the lamp, a light-deflector composed of telescoping arched sections hingedly mounted upon the exterior of the case and provided with inter-engaging members for imparting motion from one to the other of the sections when one of said sections is adjusted for use and a flange on said one of the sections for engaging and returning the remaining sections.

5. In combination with a lamp, a casing for the lamp, a light-deflector composed of telescoping arched sections hingedly mounted upon the exterior of the case and provided with inter-engaging members for imparting motion from one to the other of the sections when one of said sections is adjusted for use and a flange on said one of the sections for engaging and returning the remaining sections and automatic means for returning the flanged section.

In witness whereof I have hereunto set my hand this 24th day of September, 1912.

FREDRICK F. MACLEAN.
